CLAIM

The ornamental design for the reticle pattern for a gun scope, as shown and described.

DESCRIPTION

FIG. 1 is a front perspective view of reticle pattern for a gun scope showing our new design;

FIG. 2 is a front view, the rear side view being a mirror image of the front view thereof;

FIG. 3 is a top view, the bottom view being a mirror image of the top view thereof;

FIG. 4 is a left view, the right view being a mirror image of the left view thereof; and,

FIG. 5 is an enlarged sectional view of the reticle pattern for a gun scope taken along the lines 5—5 in FIG. 2.

The broken lines shown in all views are to illustrate environment only and form no part of the claimed design.
